H. WHITING.

LIFTING JACK.

APPLICATION FILED JAN. 11, 1912.

1,205,300.

Patented Nov. 21, 1916.

UNITED STATES PATENT OFFICE.

HORATIO WHITING, OF NEW YORK, N. Y.

LIFTING-JACK.

1,205,300.

Specification of Letters Patent. Patented Nov. 21, 1916.

Application filed January 11, 1912. Serial No. 670,544.

To all whom it may concern:

Be it known that I, HORATIO WHITING, a citizen of the United States, and a resident of New York city, in the county of New York and State of New York, have invented certain new and useful Improvements in Lifting-Jacks, of which the following is a specification.

This invention relates to a new and improved lifting jack for replacing cars or the like on the track, or for moving an object after it has been lifted from one position to another.

An object of this invention is to provide a lifting jack which will be capable of shifting an object such as a car after the same has been raised to the desired level from one point to another. This object is obtained by having a supplementary rest or head, located off-set from the main head on the riser or standard, on an arm connected to move with the riser or standard both in a vertical direction and transversely in a horizontal direction. The mechanism for raising the standard is so arranged that the standard, which in this case is shown to be in the form of a screw, can first advance vertically without rotation, so as to lift the object, on the supplementary rest or head, to the desired level, and then can be connected so as to rotate, without further raising, so as to swing the supplementary head and the object carried thereby, from its initial position to the position desired.

In the embodiment used to illustrate this invention, the operating mechanism is shown to be in the form of a worm which rotates a worm wheel having a screw threaded engagement with the riser or standard, so as to shift the same either upwardly or downwardly as desired. Locking or clutching means is provided for alternatively securing the riser or standard either to the frame or casing of the jack or to the worm wheel, so as, in the former case, to shift the standard relative to the worm wheel, and in the latter case, to rotate the standard with the worm wheel.

The mechanism for swinging the object raised can be readily detached so that the jack can act with the function of the ordinary lifting jack.

These and further features together with the construction and combination of parts will be more fully described hereinafter, and particularly set forth in the claims.

Reference may be had to the accompanying drawing in which like reference characters denote corresponding parts in the several views, and in which:

Figure 1 is a vertical section; Fig. 2 is a horizontal sectional view with the cover plate removed showing the clutching or locking means for alternatively connecting the riser or standard to the frame of the jack or to the worm wheel; Fig. 3 is a horizontal section on the line 3—3 of Fig. 1; Fig. 4 is a horizontal section on the line 4—4 of Fig. 1; Fig. 5 is a horizontal section through the auxiliary supporting ring showing a modified form thereof; Fig. 6 is a detail view of the cover plate; Fig. 7 is a fragmentary vertical section of the form shown in Fig. 5.

Referring more particularly to the separate parts of this invention as embodied in the form shown in the drawings; 1 indicates the frame or stationary casing of the jack which is provided with a somewhat centrally located opening or bore 2, extending vertically of the same. The upper portion of the casing is hollowed out to form an enclosed compartment 3, in which a portion of the actuating mechanism is located. This actuating mechanism includes a worm wheel 4, which may be supported by resting on a roller bearing 5, on the bottom of the compartment 3, in the casing 1. The worm wheel has a central opening located in alignment with the bore or opening 2, and through which extends a riser or standard 6, which is preferably in the form of a screw having screw threaded engagement with the worm wheel 4, so that as the worm wheel rotates relative to the riser or standard 6, said riser will be fed in one direction or the other according to the direction of rotation of the worm wheel 4. This may be rotated in one direction or the other by a worm 7, which may be operated by crank 8.

The standard or riser 6, may be provided with a head 9, which may be squared so as to swing therewith, when it is rotated, an arm 10 which is secured to the head 9 by having an angular socket 11. Adjacent the outer extremity of the arm 10 there is provided a supplementary rest or head 12, which may be rotatably mounted on the arm 10, as by having a stub shaft 13, engaging a cylindrical socket in the arm 10. In order to increase the ease of relative movement between the supplementary head 12 and the arm 10,

there may also be provided balls or rollers 14 between the head and the arm.

If the head 12 is considerably off-set from the head 9, it may be desirable to provide a supplementary support which will transmit the load supported by the head 10 to the frame or casing 1. For this purpose there is pivotally connected to a pin 14, located on the arm 10, beneath the rest or head 12, a thrust link 15, which may be detachably and pivotally connected to a ring 16 by a pin 17, which engages alined openings in the link 15 and flanges 18, on the ring 16. The ring 16 may be rotatably mounted so as to revolve with the swinging movement of the arm 10, on a main ring 19, which encircles the shaft of the frame 1. The connection between the ring 16 and the ring 19 may be as shown in Fig. 1 wherein it will be seen that the ring 16 is set in an annular groove in the ring 19, and held out of contact by means of roller bearings 20. In the form shown in Fig. 1 the ring 19 is provided with rollers 21 and 22, so located that, in operation of raising or lowering the riser or standard, they will readily engage the sides of the frame 1 and lessen the friction of the supplementary supporting means therewith. In order, however, that when the load settles on this supplementary supporting means, it may act as a positive connection between the arm 10, and the frame 1 there are provided jabbing points or edges 23 and 24, which are so located that when the thrust is from the arm 10 to the rings on the frame 1, these points or edges will bite into the frame or casing 1. It will be noted that the rollers 21 and 22 and the jabbing points 23 and 24, are staggered relative to each other so that the ring 19 will have different corresponding portions in engagement with the casing 1, when it is either rising or coming down, on opposite sides of the casing. In order to increase the efficiency of the lowering action, there may be located a bumper or cushion 25 of any suitable yieldable material such as rubber between the link 15 and the ring 19. This bumper will act as a spring permitting a certain amount of lowering movement of the arm 10 and the link 15 before the ring 19 is pushed downward.

In order that the off-setting mechanism can be readily detached from the jack, so that the latter can be used as an ordinary lifting jack, the ring 16 may be in the form of a split ring comprising sections 26 and 27, hinged together at 28, and secured together at their free ends by the pin 17, passing through the openings in the flanges 18.

When it is desired to raise the riser or standard to any given point, it is preferably held against rotation by being provided with a longitudinal groove or slot 29 in which engages a tongue 30 on a lock or clutch 31, which is shown in the form of a disk having

a plurality of teeth 32 and 33, adapted to engage alternatively in sockets or between corresponding teeth on a fixed member 34 and on a worm wheel 4. The fixed member 34 is shown in the form of a cover plate secured 70 so as to be fixed against rotation as by being secured to the casing 1. The lock or clutch 31 shown in the form of a disk has a circumferential groove 35 therein, in which engages pins 36 secured to a shifter 37. This 75 shifter is shown in the form of a ring encircling the casing 1, and pivotally connected thereto at 38, and also provided with a handle 39' whereby it may be manipulated. It will be seen that, inasmuch as the pins 80 36 project through slots 39 in the casing 1, and also in the groove 35, that by a movement of this shifter the lock or clutch 31 can be shifted so as to either lock the riser or standard 6 against rotary movement, or 85 lock it to rotate with the worm wheel 4. The shifter 37 can be secured in either of these positions of adjustment by a spring pressed latch 40 engaging in suitably located notches in the side of the casing 1. 90

In the form shown in Figs. 5 and 7, a modified type of ring is shown for supporting the outer end of the arm and is indicated by the numeral 41. This ring is provided on one side with pockets 42, having their deepest portion at their upper end, and their shallowest portion at their lower end. At the opposite side of ring, there are provided pockets 43 similar to the pockets 42 with the exception that they are arranged just opposite with respect to the pockets 42, that is to say, they have their deepest portion at the bottom, and their shallowest portion at the top. In these pockets 42 and 43 there are located balls 44 which are 100 adapted to bite into the outer surfaces of the casing 1, when the load is placed on the supplementary rest or head, and are adapted to move back in the deepest portion of the pocket when the riser is being lifted or 105 lowered.

The operation of the device will be readily understood when taken in connection with the above description. If desired a plurality of the jacks can be used simultaneously to lift a car bodily and replace it on the track, after it has been raised a suitable amount from the ground, by swinging the arms of the jacks either in the same direction or in different directions, according to 115 the position of the various points of the car with which the jacks are in engagement, relative to the track. In the operation of each individual jack, the clutch or lock is thrown so as to secure the riser or standard 120 against rotary movement relative to the casing 1, so that it will be free to move relative to the worm wheel by turning the crank. The riser will be fed upwardly until the weight, such as a car, resting on the supple- 125

mentary head has been raised the desired degree, then the riser can be connected so as to rotate with the worm wheel and, inasmuch as it rotates with the worm wheel 5 this wheel will no longer feed it in a vertical direction, but will swing the arm connected with the riser either to the right or to the left according to the direction by rotation of the crank and the worm. It will be seen that it is not necessary to rotate the worm in the same direction as is necessary 10 to raise the jack, but it can be rotated likewise in the opposite direction without danger of lowering the riser and the load supported on the supplementary rest. The load which may be a car will thus be swung the desired degree, which, if desired may be through the complete arc of a circle. The eccentric thrust of the load may be carried 15 to the casing adjacent the base thereof by the supplementary supporting means, which is permitted to rotate without friction in either form or modification.

While I have shown two embodiments of 25 my invention, I do not wish to be limited to the specific details thereof, but desire to be protected in various changes, alterations and modifications which may come within the scope of the appended claims.

Having thus described my invention what I claim is:

1. The combination with a casing, of a standard mounted for vertical movement in 35 said casing, a head on said standard for supporting a load and a unitary means for alternatively advancing said standard or rotating the same *in situ*.

2. The combination with a casing, of a standard mounted for vertical movement in 40 said casing, a head eccentrically located with respect to the axis of said standard and arranged to move with said standard both vertically as when said standard advances and horizontally as when said standard rotates, and a unitary means for alternatively advancing said standard or rotating said standard *in situ*.

3. The combination with a casing, of a 50 riser movably mounted in said casing, actuating means for said riser, and means for alternatively fixing said riser against rotation and fixing said riser to a part of said actuating means for rotation therewith.

4. The combination with a casing, of a 55 riser movably mounted in said casing, actuating means for said riser, and means for alternatively fixing said riser against rotation and fixing said riser to a part of said actuating means for rotation therewith, and 60 a head off-set out of alinement with said riser movable through the arc of a circle with the rotation of said riser and movable vertically with the longitudinal movement of said riser.

5. The combination with a casing, of a

riser mounted in said casing, a worm wheel for operating said riser, a worm for actuating said worm wheel and locking means for alternatively fixing said riser for rotation with said worm or fixing said riser against 70 rotation with said worm.

6. The combination with a casing, of a 75 riser mounted in said casing, a worm wheel for operating said riser, a worm for actuating said worm wheel, and locking means for alternatively locking said riser to said worm or to said casing, and means for securing said locking means in any position of adjustment.

7. The combination with a casing, a screw 80 threaded member, the standard having a threaded engagement with said member, and a common means enabling either an unprogressive rotary movement of said standard or a progressive rectilineal movement of 85 said standard.

8. The combination with a casing, of a 90 riser, means for raising and rotating said riser relative to said casing, and a load-carrying head supported upon said riser independently of said means, said head being secured for rotatory movement with and located out of vertical alinement with said riser so that a rotary movement of said riser will swing said head through the arc of a 95 circle with the axis of the riser as a center.

9. The combination with a casing, of a 100 riser, a revolvably mounted member having a threaded engagement to said riser, a single means for alternately rendering said screw revolvble relative to said revolvably mounted member or rigid relative thereto, a head for supporting a load secured for rotatory movement with and located out of vertical alinement with said riser so that a rotary movement of said riser will swing said head through the arc of a circle having the axis 105 of said riser as a center, and a supplementary support for transferring the load on said head to said casing.

10. The combination with a casing, of a 110 riser, means for raising said riser, an arm connected to said riser, a head on said arm, and a supplementary support extending from said arm to said casing comprising a link connected to said arm, and a ring detachably connected to said link and encircling said casing so as to be rotatable and movable bodily relative thereto.

11. The combination with a casing, of a 115 riser, means for raising said riser, an arm connected to said riser, a head on said arm and a supplementary support extending from said arm to said casing comprising a link connected to said arm and a ring connected to said link and encircling said casing, said ring having gripping and anti-friction means engaging said casing.

12. The combination with a casing, of a 120 rotary member supported by said casing and 125

having a screw-threaded opening therein, a screw engaging said opening, a head connected to said screw, a member fixed to said casing, and locking means connected to said screw shiftable to fixedly engage alternatively either of said members to determine the character of movement of said screw.

13. The combination with a casing, of a rotatable riser, a load-carrying head for said riser eccentrically located with respect to the axis of rotation of said riser, said riser being movable to raise said head, and means controllable independently of said load-carrying head for rotating said riser *in situ* to swing said head through a flat arc while said riser remains at the same level.

14. The combination with a casing, of a worm wheel supported by said casing and having a screw-threaded opening therein, a screw engaging said opening so as to be moved longitudinally by a rotary movement of said worm wheel, a head connected to said screw and located out of axial alinement therewith but connected to rotate therewith so as to swing through the arc of a circle when said screw rotates, said screw having a slot therein, and a locking clutch having a tongue engaging in said slot, and being movable to secure said screw either against rotary movement with said worm wheel or for rotary movement with said worm wheel, said casing and said worm wheel having means to enable the locking of said clutch therewith.

15. The combination with a casing of a 35 rotary member supported by said casing and having a screw threaded opening therein, a screw engaging said opening, a head connected to said screw, a member fixed to said casing, and locking means connected to said screw shiftable to fixedly engage alternatively either of said members to determine the character of movement of said screw, and means for rotating said first mentioned member. 45

16. The combination with a casing, of a riser, an actuating member, and a single locking mechanism alternatively connecting said riser non-rotatably to said casing or said member so as to afford a relative rotation between said riser and said member or said riser and said casing. 50

17. The combination with a casing, of a standard mounted in said casing, a handle for driving said standard, a gearing operated by said handle for effecting an unprogressive rotary movement of said standard at a slower speed than said handle and locking means for enabling said handle to effect a rectilineal movement of said standard. 55 60

Signed at New York city, in the county of New York and State of New York, this 10th day of January, A. D. 1912.

HORATIO WHITING.
